CLAIM

The ornamental design for a bow making apparatus, as shown and described.

DESCRIPTION

FIG. 1 is a perspective view of a bow making apparatus showing our new design;

FIG. 2 is a top plan view thereof;

FIG. 3 is a front elevation view thereof;

FIG. 4 is a bottom plan view thereof;

FIG. 5 is a rear elevation view thereof;

FIG. 6 is a right side elevational view thereof; and,

FIG. 7 is a left side elevational view thereof.

The broken lines, including the numerals represented in broken lines, in FIGS. 1 and 2 form no part of the ornamental design claimed herein.
